(57) **CLAIM**

The ornamental design for a pacifier clip, as shown and described.

DESCRIPTION

FIG. 1 is a rear perspective view of the pacifier clip showing my design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom side view thereof; and,

FIG. 8 is a rear perspective view of the pacifier clip of FIG. 1, shown for clarity of disclosure in a condition of use connected to a pacifier.

Portions of the design and the pacifier shown in broken lines form no part of the claimed design.

1 Claim, 3 Drawing Sheets
